J. B. Northern Inventor

Jack Keeley
Attorney

UNITED STATES PATENT OFFICE.

JOSEPH B. NORTHERN, OF DALLAS, TEXAS.

RADIATOR CAP FOR MOTOR VEHICLES.

Application filed November 1, 1921. Serial No. 511,977.

To all whom it may concern:

Be it known that I, JOSEPH B. NORTHERN, a citizen of the United States, residing at Dallas, in the county of Dallas and State of Texas, have invented certain new and useful Improvements in Radiator Caps for Motor Vehicles, of which the following is a specification.

This invention relates to new and useful improvements in radiator caps for motor vehicles.

The object of the invention is to provide highly improved means for closing the filling opening in radiators of automobiles, trucks, tractors, aeroplanes, and the like. A further object is to provide means for expeditiously opening and closing the filling opening, without the usual discomfort and inconvenience experienced by the operator when the radiator stem is hot.

In carrying out the invention I provide a cylindrical sleeve adapted to be threaded on the stem of a radiator surrounding the opening, said sleeve having a cap hinged to one side at the top which carries a cam adapted to engage a lug cast on the opposite side of the sleeve.

A construction designed to carry out the invention will be hereinafter described together with other features of the invention.

The invention will be more readily understood from a reading of the following specification and by reference to the accompanying drawings, in which an example of the invention is shown and wherein:

Fig. 1 is a side elevation of a radiator cap embodying my invention,

Fig. 2 is a plan view with a portion broken away showing the pivot pin of the link,

Fig. 3 is a vertical sectional view taken on the line 3—3 of Fig. 2, and

Fig. 4 is a detail showing a front elevation of the locking mechanism.

In the drawings the numeral 10 designates a cylindrical sleeve having an upwardly inclined shoulder 11 which merges into an annular flange 12 at the lower end of the sleeve. The flange is internally screw threaded to engage the threads of a radiator stem 13, as is shown in Fig. 3. However, it is understood that the base of the sleeve may assume any practical shape, and that it may be externally threaded so as to engage internal threads of a radiator stem,

when it is so desired. In order to provide a water-tight joint the base of the flange 12 may be soldered to the top 14 of a radiator.

Cast on one side of the sleeve near the top 60 are ears 15 which have corresponding apertures 15'. On the opposite side of the sleeve, a lug 16 is casted. The position of the lug is slightly lower than the ears 15 with relation to the top of the latter. A 65 cap 17 has a concavo-convex crown 17' which merges into an annular flange 18. Cast on the flange is a depending lug 19 having an aperture adapted to align with the apertures 15' of the ears 15 when the top 70 of the sleeve is covered by the cap. The lug engages between the ears 15 and a pin 20 passed thru the said apertures, whereby the cap is hinged on the sleeve. An annular gasket 21 is integral with the crown and 75 projects inwardly of the sleeve. The gasket engages the top of the sleeve when the latter is closed so that a water-tight cover may be had.

Opposite the lug 19 a slot 22 is provided 80 in the flange 18. The slot receives the upper reduced end of a link 23 which is pivoted on a pin 24. A slot 25 adapted to receive the lug 16 is provided in the said link, and a cam 26 is pivoted in the lower portion of 85 the slot on a pin 27. The cam merges into a lever 28, the said cam being adapted to engage in a notch 29 in the underside of the lug 16.

It will be readily seen that the cap may 90 be readily raised by pulling the lever upwardly and forwardly so that the cam will disengage the lug 16, as is shown in dotted lines in Fig. 1. When the cap is lowered the cam automatically rides over the lug 16 95 and the latter engages in the slot 25 of the link. By swinging the lever downwardly the cam is securely engaged in the notch 29 and against the outside of the sleeve. It will be seen that the lever is not swung to a 100 perpendicular position, but is inclined outwardly. By this arrangement it is obvious that as the notch 29 wears the lever may be pushed inwardly, whereby the cam will still frictionally engage in said notch to 105 hold the gasket 21 frictionally against the top of the sleeve.

When it is desired a hole, as is shown in dotted lines in Fig. 2, may be provided in the center of the crown so that a motor 110

meter may be suitably mounted on the cap. It is pointed out that a device constructed in accordance with my invention provides an efficient means for covering the filling opening of the radiator of a motor vehicle. The cap may be quickly raised or lowered without inconvenience or discomfort to the operator, and when the cam is in engagement in the notch 29, and with the outside 10 of the sleeve the cap provides a water-tight cover for the sleeve.

Various changes in the size and shape, as well as modifications, may be made without departing from the spirit of the invention.

15 What I claim, is:

In a radiator filling cap structure, an elongated upright sleeve having its lower end arranged for securing to the filling collar of a radiator, a pair of hinge ears at 20 the upper edge of the sleeve, a cap having an annular seat in its underside, a gasket

ring fitting in said seat and engaging on the upper edge of the sleeve, the cap having an annular flange overhanging the sleeve and directed outwardly therefrom, a 25 lug depending from said flange and hinged between the ears, the flange having a slot in its front edge diametrically opposite the lug, a link having its upper end hinged in the slot and provided with a slot extending upwardly from its lower end, a cam pivoted in the lower end of the link slot, a lever extending from the cam, and a radial lug extending from the sleeve and engaged in the slot immediately over the cam, which is frictionally engaged with the underside of said lug when swung by the lever, the lever at all times being free from contact with the sleeve so as to provide finger space therebetween.

In testimony whereof I affix my signature.

JOSEPH B. NORTHERN.
